Firestone Maxi Traction, tire, undated.
Firestone Radial All Traction 23°, tire, undated.Primary Examiner — George D. Kirschbaum
Assistant Examiner — Joseph J Kukella(57) **CLAIM**

The ornamental design for a tire tread, as shown and described.

DESCRIPTION

FIG. 1 is a side perspective view of a first embodiment of a tire tread showing our new design, it being understood that the tread pattern is repeated throughout the circumference of the tire tread, the opposite side being the same as that shown; FIG. 2 is a front elevational view thereof, the opposite side being identical thereto; and, FIG. 3 is a side elevational view of the left side thereof, the opposite side being identical thereto. In the drawings, the shaded surfaces comprise the claim. The broken lines defining the sidewall, inner bead, and the peripheral boundary between the claimed tire tread and the sidewall depict environmental subject matter that forms no part of the claimed design.
